United States Patent Office

Des. 220,570
Patented Apr. 27, 1971

220,570

PLAQUE OR SIMILAR ARTICLE

Robin C. Houston, Pittsfield, Mass., assignor to
Textron Inc., Pittsfield, Mass.

Filed Apr. 1, 1970, Ser. No. 22,163

Term of patent 14 years

Int. Cl. D11—99

U.S. Cl. D29—23

FIG. 2

FIG. 6

FIG. 3

FIG. 4

FIG. 5

FIG. 1 is a rear elevational view of the back plain and unornamented side of a plaque embodying my new design, the front ornamented side of which is shown in FIGS. 2, 3, 4 and 5;

FIG. 2 is a front elevational view on a much enlarged scale of the top right quadrant of the front face thereof;

FIG. 3 is a front elevational view on a much enlarged scale of the bottom right quadrant of the front face thereof;

FIG. 4 is a front elevational view on a much enlarged scale of the bottom left quadrant; and of the front face thereof;

FIG. 5 is a front elevational view on a much enlarged scale of the top left quadrant of the front face thereof;

FIG. 6 is a diametric cross sectional view of the plaque.

Details around the circle portion and in the keystone portion continue as indicated being the same as shown in the left segment of FIG. 2.

I claim:

The ornamental design for a plaque or similar article, substantially as shown and described.
